United States Patent Office

Des. 202,418
Patented Sept. 28, 1965

202,418

VEHICLE ROOF

Thomas P. O'Donnell, Queens County, N.Y.
(220 Highland Blvd., Brooklyn, N.Y.)

Original application Dec. 27, 1960, Ser. No. 63,338, now
Design Patent No. 198,127, dated May 5, 1964. Di-
vided and this application Oct. 22, 1962, Ser. No.
72,212

Term of patent 14 years

(Cl. D14—27)

Fig. 1.

Fig. 2.

FIG. 3.

FIG. 4.

FIG. 5.

FIG. 1 is a perspective view of a vehicle roof in closed position, showing my new design.

FIG. 2 is a perspective view thereof in open position.

FIG. 3 is a perspective view of a modified form thereof in closed position.

FIG. 4 is a perspective view of FIG. 3 in open position.

FIG. 5 is a perspective view of FIG. 3 in another open position.

This application is a division of my companion co-pending application Ser. No. D. 63,338 filed Dec. 27, 1960, and now Patent No. D. 198,127 issued May 5, 1964. The dominant features of my design reside in the portions shown in full lines.

I claim:

The ornamental design for a vehicle roof, substantially as shown and described.
